(57) **CLAIM**

The ornamental design for a shoe, as shown and described.

DESCRIPTION

FIG. 1 is a front view of a first embodiment of a shoe embodying our new design;

FIG. 2 is a rear view of the first embodiment of the shoe embodying our new design; and

FIG. 3 is a side view of the first embodiment of the shoe embodying our new design.

FIG. 4 is a front view of a second embodiment of a shoe embodying our new design;

FIG. 5 is a rear view of the second embodiment of the shoe embodying our new design; and

FIG. 6 is a side view of the second embodiment of the shoe embodying our new design.

The broken lines in the drawings are included for the purpose of illustrating environmental structure and form no part of the claimed design.

1 Claim, 6 Drawing Sheets
